UNITED STATES PATENT OFFICE.

CAESAR NEUMANN, OF NEW YORK, N. Y.

SKELETON SKIRT.

Specification of Letters Patent No. 26,514, dated December 20, 1859.

To all whom it may concern:

Be it known that I, CAESAR NEUMANN, of the city, county, and State of New York, have invented certain new and useful Improvements in Hoop-Skirts, some of the devices in which may be applicable to other purposes; and I do hereby declare and ascertain my said improvements, referring to the accompanying drawing, in which—

10 Figure 1, shows the skirt expanded; Fig. 2, the same collapsed; Fig. 3, details.

My improvement is, first, for the purpose of readily collapsing hoop skirts at the will of the wearer, so as to contract the same 15 when entering stages or otherwise or seating one's self, and this can easily be done at the will of the wearer, while the skirt will again readily assume its expansion when released.

The construction is as follows: The skirt 20 is made in any of the known ways that may be found convenient, but the springs which run horizontally around the skirt, instead of being one continuous piece, as in ordinary skirts, are jointed, as seen in the drawing.

25 The springs are lettered a a' a^2 ; the hinge joints, b . About two-thirds of the spring, more or less, is in one piece a . On each end of this piece is jointed a short piece a' , and these two short pieces a' are jointed to each

30 end of a short piece a^2 . The hinges that form these joints are made so as to open out like a rule joint, only to bring the pieces into the line of the circle, the ones connected with the long piece a being turned so as to 35 allow those ends to be bent inward and the others in a reverse direction, as clearly seen in the drawing. These hinges are made with a projecting knuckle joint, having a straight surface on one side when open, the

40 parts of the two halves of the hinge that are pivoted together being bent at right angles

to the other part, so as to make a short lever-
age therewith and when open to rest against each other to prevent the further movement of the ends of the hinges that are affixed to 45 the springs above named. There is a strip of some elastic material, such as india rubber, stretched from one piece to the other of the shanks of this hinge, so as to hold them in line or the spring open at all times except 50 when a superior pressure folds up the hinge. Hinges thus constructed and applied to the hoops as herein set forth will cause the hoops to remain expanded unless pressed upon, when they will collapse, bending the rear 55 end inward and the front end outward, causing that portion of the hoop to fold over, so as to reduce its size about one-third, more or less. More joints may be added as desired.

When this skirt thus made is on the wearer 60 she has only to press her hand upon the sides at or about the point of the rear hinges, when they will at once fold inward, and thus reduce the size.

It may be proper to add that the lower 65 springs may be furnished with joints without springs, which follow the movement of the upper ones, in which the springs are placed within the range of the hands of the wearer.

Having thus described my improvements, what I claim, and desire to secure by Letters Patent, is—

The spring joint or hinge arranged and constructed as herein specified by which the 75 hoop can be contracted and expanded substantially in the manner and for the purposes set forth.

CAESAR NEUMANN.
